UNITED STATES PATENT OFFICE.

CHARLES DE LUKACSEVICS, OF WEST NUTLEY, NEW JERSEY, ASSIGNOR TO DANE MANUFACTURING COMPANY, OF EAST ORANGE, NEW JERSEY, A CORPORATION OF NEW JERSEY.

SIPHON-HEAD.

1,124,927.

Specification of Letters Patent.

Patented Jan. 12, 1915.

Application filed November 15, 1913. Serial No. 801,224.

To all whom it may concern:

Be it known that I, CHARLES DE LUKACSEVICS, a citizen of the United States, residing at West Nutley, in the county of Essex and 5 State of New Jersey, have invented new and useful Improvements in Siphon-Heads, of which the following is a specification.

This invention relates to improvements in siphon heads, of the general type 10 closed in my prior U. S. Patents No. 1,040,226, granted Oct. 1, 1912, and No. 1,061,857, granted May 13, 1913.

The invention is directed to certain improvements in details of structure and arrangement which concern the construction 15 of the valve of the head whereby the said valve and its appurtenances have great strength, are without any exposed metallic surfaces, and, consequently, are not liable 20 to corrosion and provide an efficient seal against the escape of gas through the head, even though the latter be made of porcelain or similar porous material; the relation of the parts of the siphon head to one another 25 whereby an especially efficient and facile assemblage of said parts is provided for; the assemblage of the siphon head upon the bottle neck whereby the head is accurately aligned with the bottle and the joint between 30 said neck and said head is effectively sealed, regardless of any irregularities or other defects of the surface of the mouth of the bottle; and the assemblage of the siphon tube relatively to the head whereby said tube is 35 strongly supported, is not liable to displacement, and may be readily and quickly applied to and removed from the head.

An embodiment of the invention is illustrated in the accompanying drawings, 40 wherein:—

Figure 1 is a vertical sectional view of a siphon head in which the features of the invention are incorporated; Fig. 2 is a view showing in detail, by way of elevation 45 and section, the various elements employed in the valve stem construction; Fig. 3 shows, in plan and in sectional detail, the construction of the elastic valve head; Fig. 4 shows in vertical section the organized relation of 50 the metal valve stem and the elastic valve head; Fig. 5 is a view showing in plan and sectional detail the valve operating knob and its immediate appurtenances; Figs. 6 to 10 are views showing in plan and 55 sectional detail various elements which par-

ticipate in the assemblage of the siphon head upon the bottle neck and in the connection of the siphon tube and the siphon head.

Similar characters of reference designate corresponding parts throughout the several 60 views.

The improvements are illustrated in connection with a porcelain head, designated generally as 1, and having its lower end in the form of an enlarged socket 2, which fits 65 over the bottle neck 3 and is held in position by a suitable means, such, for example, as the coöperating securing rings 4 and 5, associated with the socket and with the neck respectively.

The head 1 is formed inwardly of the socket 2 with a bell-shaped or generally globular cavity 7 which, at its lower end, communicates with said socket and at its upper end communicates with an axially 70 disposed liquid conducting passage 8, from which branches the usual liquid discharge duct 9. The cavity incloses a bell-shaped member 10 of hard or relatively hard rubber and this member 10 serves four functions; first, to seal the joint between the bottle neck and the siphon head against the escape of gas from the bottle through any pores or interstices of the siphon head; second, to furnish support for the siphon tube 85 6 and to constitute a connection between said tube and the siphon head; third, to provide a housing for the valve; and fourth, to maintain the siphon head in perpendicular alignment with the bottle and to provide 90 for the efficient and gas-tight connection of said head and bottle, regardless of any irregularities or other defects of the surface of the mouth of the bottle.

The member 10 is provided with a circum- 95 scribing annular flange 11 to engage over the mouth of the bottle, and with an annular depending flange 12, which projects into the mouth of the bottle and is internally threaded to receive an externally threaded 100 hard rubber sleeve 13, which carries the siphon tube 6. It is preferred to interpose sealing gaskets between the member 10 and the parts adjacent thereto. Thus, a gasket 14 is arranged between the flange 11 and the upper surface of the bottle neck; a gasket 15 is arranged between the upper portion of the member 10 and the upper portion of the cavity 7; and a gasket 16 is arranged 105 between the flange 12 and a flange 17 which 110

circumscribes the sleeve 13. The member 10, at its upper end, is formed with an opening 18 which aligns with the passage 8, and adjacent and below said opening with a valve seat 19. The valve is designated generally by the numeral 20, and its stem projects through the opening 18, while its head is disposed within the internal cavity of the member 10 and cooperates with the valve seat 19. The cavity 7, as above stated, is of generally globular or bell-shaped form and the external surface of the member 10 is similarly and conformably fashioned. Where a gasket is interposed between the member 10 and the wall of the cavity 7, as in the construction shown, said gasket, *i. e.* the gasket 15, has a convex outer face and is preferably of concavo-convex form.

By virtue of the relation of the generally globular adjoining faces of the cavity 7 and the member 10, the siphon head can always be held in perpendicular alinement with the bottle, notwithstanding that the member 10 may occupy a slightly canted position, by reason of irregularities or other defects in the upper surface of the bottle neck.

Owing to the fact that gas-tight seals are provided between the member 10 on the one hand and the bottle neck and the siphon head on the other hand, any leakage of gas when the valve is in closed position, is effectively prevented.

The valve 20 is preferably of the construction shown in the drawings and comprises the relatively thin metal stem 21, the elastic valve head 22, the hard rubber sleeve 23 which surrounds the stem 21 and clamps the valve head on said stem, and the nuts 24 mounted upon the threaded upper portion of the stem and engaging the upper end of the sleeve 23 to cause the latter to exert clamping pressure upon the valve head.

The rubber valve head 22 is held with strong pressure against the seat 19 and in order that said valve head may be rigidly supported, and hence, pressed securely against said seat, and at the same time may not be liable to wear or to become loose upon or stripped from the lower end of the stem 21, and further, in order that no area of metal, however small or minute, may be exposed, the construction shown in the drawings is adopted, according to which the valve head 22 is in the form of a cone, the valve stem 21 terminates at its lower end in a conical or flaring enlargement 25 which fits in a conical or flaring recess 26 in the valve head 22, and the sleeve 23 has a conical or flaring enlargement 27 at the lower end of its bore which receives the upper portion of the valve head and by virtue of which the sleeve acts with clamping pressure on the valve head and the metal of the

stem is not only concealed, but is sealed against the access thereto of any corrosive liquid or gas.

The head 1 is formed above the passage 8 with a web 28 having a central opening, and the valve stem 21 and also the sleeve 23 project through the opening 18 in the upper end of the member 10, through the passage 8 and through the opening in the web 28. Above the web 28 the head 1 is formed with a socket 29 in which works the operating knob 30. The valve stem 21 has its upper end secured to the knob 30 and the latter has an internal cavity in which is mounted an expansive coil spring 31. The spring 31 maintains the closed relation of the valve and surrounds the stem 21, said spring at its upper end engaging the knob 30 and at its lower end engaging the web 28. The opening in the web 28 is sealed by a gasket or packing ring 32, which snugly surrounds the sleeve 23. The ring 32 is preferably located at the upper side of the web 28 and in order to protect said ring against wear, a metal washer or other wear ring 33 is imposed thereon to take the thrust of the spring 31.

Instead of the usual direct-thread connection between the upper end of the valve stem and the operating knob, the construction shown in the drawings may be advantageously employed, according to which the knob 30 has a central opening 34 of substantially greater diameter than the valve stem 21 and formed with threads or serrations and a soft metal ring 35 is cast in this opening, the metal of said ring interlockingly engaging in the threads or serrations of the opening 34 and the threads of the valve stem 21. The opening 34 and the valve stem 21 originally define an annular mold space into which the metal forming the ring 35 is poured, and said mold space is closed at its lower end by a ring 36 arranged at the upper end of the internal cavity of the knob 30 and receiving the thrust of the spring 31.

In order to limit the downward movement of the knob 30 the socket 29 is formed with a step 37 and said knob is formed with an external shoulder 38 for engagement with said step. In order to prevent rotation of the knob 30 the latter is formed with a facet 39 below the shoulder 38 and the socket 29 is formed with a similar facet below the step 37.

In assembling the siphon head the valve parts shown in Fig. 2 are first organized in the manner explained. The member 10 is then centered in the cavity 7 and the valve stem is introduced into the cavity of said member and is pushed through the opening 18, the passage 8, and the opening 28, into the socket 29. The nuts 24 are preferably round and of the same diameter as the sleeve 23, in order to avoid interference with the assembly of the valve in the siphon head, in

the manner just stated. The spring 31 is next placed in position in the socket 29 and the knob 30 is then fitted in said socket over said spring. The knob and valve stem are 5 so held by any suitable appliance that the annular mold cavity, previously referred to, is defined, the ring 36 forming the bottom of this cavity, as already explained. Thereupon, the ring 35 is cast in said cavity, and 10 when the metal of said ring sets a secure connection is provided between the valve stem and the knob, as is obvious. In case it is desired to dismantle the valve, a soldering iron or other suitably heated implement is 15 used to soften the ring 35, whereupon the knob 30 may be disconnected from the valve stem and the parts dismantled as is obvious. The use of the cast ring 35 is of advantage in that it protects the knob 30 against fracture 20 and promotes the facility of assemblage and disassemblage of the parts of the siphon head.

The upper end of the siphon tube 6 is cemented in the sleeve 13 and to facilitate the 25 union of said tube and said sleeve, the central opening of the latter terminates in flaring enlargements 40, in which the cementing agent is introduced. That portion of the sleeve 13 below the flange 17 is formed with 30 openings or recesses 41 for engagement by the jaws of a spanner or other suitable implement employed to rotate the sleeve 13 in effecting the connection or disconnection of said sleeve and the member 10.

35 The valve head 22 holds the member 10 in position in the cavity 7 and thus supports said member and the siphon tube whenever the siphon head is in detached relation.

The siphon head described, although of 40 extremely simple structural nature and being relatively inexpensive to manufacture, is particularly efficient in use, in that effective provision is made against the escape of gas, compensation is made for irregularities or 45 other defects in the upper surface of the bottle neck, the siphon tube is strongly supported, cushioned against jars, and removable and replaceable with facility, the valve is organized with especial regard to sanitation, and is especially effective in its action 50 and durable in its nature, the assemblage and disassemblage of the parts of the siphon may be accomplished easily and quickly, and no particular care in surfacing any part of the 55 internal cavity of the head proper is required, since the efficiency of the seals and of the seating of the valve does not depend on the exact evenness or uniformity of the surfaces of the cavity of the siphon head and 60 the valve body does take directly against a seat formed in the member 10 rather than against a seat formed in the siphon head proper. This last advantage is particularly important in cases where the siphon head is 65 made of porcelain or like material, which,

by reason of its porous nature and the treatment required in manufacture, is very likely to develop surface irregularities, and, if not effectively sealed, to allow the leakage of 70 gas.

Having fully described my invention, I claim:

1. In combination, a siphon head having a socket to fit over a bottle neck and having an internal cavity opening from said socket, 75 a member of non-corrosive and non-porous material fitted upon the upper surface of the bottle neck and disposed within said cavity, the member having an opening therethrough in which is formed a valve 80 seat, the siphon head having a liquid passage above the member, a valve head located within the opening of said member and under said valve seat with which it coacts, a stem carrying said valve head and 85 projecting through the upper end of said member and through said liquid passage, and operating means associated with the upper end of said stem and normally holding the valve to its seat, said valve holding said 90 member within said cavity, the member having sealing engagement with said bottle neck and with said internal cavity and the valve head having sealing engagement with said member. 95

2. In combination, a siphon head having a socket to fit over a bottle neck and having an internal generally globular cavity opening from said socket, a member of non-corrosive and non-porous material fitted upon the upper surface of the bottle neck and disposed within said cavity, the member having an opening therethrough in which is formed a valve seat and having also a generally globular external face, the siphon 100 head having a liquid passage above the member, a valve head located within the opening of said member and under said valve seat with which it coacts, a stem carrying said valve head and projecting through the upper end of said member and through said liquid passage, and operating means associated with the upper end of said stem and holding the valve to its seat, said valve holding said member within said 105 cavity, the member having a sealing engagement with said bottle neck and with said internal cavity and the valve head having sealing engagement with said member. 110

3. In combination, a siphon head having a socket to fit over a bottle neck, and having an internal generally globular cavity opening from said socket, a member of non-corrosive and non-porous material fitted upon the upper surface of the bottle neck and 120 disposed within said cavity, a siphon tube carried by and depending from said member, the member having a generally globular external surface conforming to the generally globular surface of said cavity and 125 130

- having sealing engagement with said cavity, with the bottle neck and with the siphon tube, the siphon head having a liquid passage, and a valve normally closing 5 the entrance to said liquid passage.
4. In combination, a siphon head having a socket to fit over a bottle neck, and having an internal generally globular cavity opening from said socket, a member of non-corrosive and non-porous material fitted upon 10 the upper surface of the bottle neck and disposed within said cavity, a siphon tube carried by and depending from said member, the member having a generally globular external surface conforming to the generally 15 globular surface of said cavity and having sealing engagement with said cavity, with the bottle neck, and with the siphon tube, the siphon head having a liquid passage 20 communicating with the interior of said member, and a valve coöperating with said member as a valve seat normally closing the entrance to said liquid passage and holding the member within said cavity.
5. In combination, a siphon head having 25 a socket to fit over a bottle neck, a cavity opening inwardly from said socket, and a liquid passage communicating with said cavity, a valve normally closing the entrance of said liquid passage, a member of 30 non-corrosive and non-porous material fitted in said cavity and having sealing engagement with said bottle neck and with said cavity, the member having an internally 35 threaded bore, a siphon tube, and a hard rubber sleeve in which the end of the siphon tube is secured, the sleeve having threaded engagement in the threaded bore of said member, the valve holding the member 40 within said cavity.
6. In a siphon head, a siphon tube, a hard rubber sleeve which fits closely in surrounding relation upon the upper end of the tube, the sleeve having its bore provided with a 45 flaring terminal enlargement and a filling of cement within said enlargement to secure the sleeve upon the tube.
7. In combination, a siphon head, a sealing member interposed between the siphon 50 head and the bottle upon which it is fitted, a siphon tube, and a hard rubber sleeve in which the upper end of the siphon tube is cemented and which is constructed for detachable connection to said sealing member.
8. In combination, a siphon head having 55 a liquid passage, a valve seat below the liquid passage, a valve stem having at its lower end a valve head for coöperation with said seat, the siphon head having a socket at its upper end and the valve stem projecting into the socket, an operating knob 60 mounted in the socket and having an opening of substantially greater diameter than the valve stem which it surrounds, and a ring of soft metal cast in said opening and

forming a rigid connection between the valve stem and the knob.

9. In combination, a siphon head having a liquid passage, and a web above the liquid passage, a valve seat below the liquid passage, 70 a valve stem having at its lower end a valve head for coöperation with said seat, the siphon head having a socket at its upper end and the valve stem projecting into the socket, an operating knob mounted in the 75 socket and having an opening of substantially greater diameter than the valve stem which it surrounds, a spring arranged in the socket and bearing at its lower end against the web and at its upper end against the knob, a ring taking the thrust of the upper end of the spring and forming a base for said opening, and a ring of soft metal cast in the space defined by said opening, 80 said valve stem and said first named ring, 85 and forming a rigid connection between the valve stem and the knob.

10. In combination, a siphon head having an internal cavity and a liquid passage 90 above the cavity, a member of non-corrosive and non-porous material fitted in the cavity and having an opening communicating with the liquid passage and a valve seat below the opening, the member having sealing engagement with the cavity and with 95 the neck of the bottle upon which the siphon head is carried, a valve head coöperating with said seat and holding the member in the cavity, a valve stem carrying said head and projecting through said opening and 100 said liquid passage, and operating means associated with the upper end of said stem.

11. In combination, a siphon head having an internal cavity and a liquid passage 105 above the cavity, a member of non-corrosive and non-porous material fitted in the cavity and having an opening communicating with the liquid passage and a valve seat below the opening, the member having sealing engagement with the cavity and with 110 the neck of the bottle upon which the siphon head is carried, a valve head coöperating with said seat and holding the member in the cavity, a valve stem carrying said head and projecting through said opening and 115 said liquid passage, and operating means associated with the upper end of said stem, the cavity being of generally globular form and the member having a generally globular external surface conforming to the generally 120 globular outline of the cavity.

12. In combination, a siphon head having an internal cavity and a liquid passage 125 above the cavity, a member of non-corrosive and non-porous material fitted in the cavity and having as an integral part thereof a valve seat which forms the entrance of said passage, and a valve head coacting with said seat, the member having sealing engagement with the cavity and with the 130

neck of the bottle upon which the siphon head is carried.

13. In combination, a siphon head having an internal cavity and a liquid passage 5 above the cavity, a member of non-corrosive and non-porous material fitted in the cavity and having as an integral part thereof of a valve seat which forms the entrance of said passage, and a valve head coacting 10 with said seat, the member having sealing engagement with the cavity and with the neck of the bottle upon which the siphon

head is carried, the cavity being of generally globular form and the member having a generally globular external surface conforming to the generally globular outline of the cavity. 15

In testimony whereof I have hereunto set my hand in presence of two subscribing witnesses.
